UNITED STATES PATENT OFFICE

99,601

DESIGN FOR A SHOE BUCKLE

Carmen S. Felch, Providence, R. I., assignor to Ernest E. Weller, Providence, R. I.

Application March 31, 1936, Serial No. 61,874

Term of patent 3½ years

To all whom it may concern:

Be it known that I, Carmen S. Felch, a citizen of the United States of America, residing in Providence, county of Providence, State of Rhode Island, have invented a new, original, and ornamental Design for a Shoe Buckle, of which the following is a specification, reference being had to the accompanying drawing forming a part thereof.

Fig. 1 is a top plan view of a shoe buckle, showing my new design; Fig. 2 is an edge view; and Fig. 3 is a side elevational view of the same.

The predominating feature of this design is a plurality of central bars with symmetrically arranged knobs positioned on either side of the group of bars.

I claim:

The ornamental design for a shoe buckle, substantially as shown and described.

CARMEN S. FELCH.
